UNITED STATES PATENT OFFICE.

CUTHBERT BURNETT, OF HARTLEPOOL, COUNTY OF DURHAM, ENGLAND.

APPARATUS FOR RAISING WATER.

SPECIFICATION forming part of Letters Patent No. 325,588, dated September 1, 1885.

Application filed April 17, 1885. (No model.) Patented in England October 6, 1883, No. 4,755; in France May 15, 1884, No. 162,136, and in Belgium May 24, 1884, No. 65,262.

To all whom it may concern:

Be it known that I, CUTHBERT BURNETT, a subject of the Queen of Great Britain, residing at Hartlepool, in the county of Durham, England, engineer, have invented certain new and useful Improvements in Apparatus for Raising Water and other Liquids, of which the following is a specification.

This invention refers to an application applied for by me on 24th of October, 1884, Serial No. 146,350, for "improvements in apparatus for raising water and other liquids," and particularly relates to the construction and application of steam-sniffing valves, whereby I admit steam instead of air for the purpose of destroying the vacuum in the body of the pump, the advantage of steam instead of air sniffing valves obviously being that on the admission of steam from the main steam-port there will be less condensation than if cold air had been admitted by an air-sniffing valve. These steam-admission and steam-sniffing valves are, as described in the specification of application for patent before mentioned, fixed on the top of the apparatus or pump, an equilibrium-valve being employed for the steam-admission, and attached to the said valve is a piston, the top of which is open to the atmosphere. A spindle for the purpose of starting the valve is provided. In some cases I may employ a spring or weight to assist the valves in closing promptly, all as described in the before-mentioned specification, and in the valve-spindle, or prolongation of the valve-spindle, there is placed a steam-sniffing valve for the admission of a small quantity of steam from the main steam-inlet.

Figure 1 of the accompanying drawings shows such a steam admission and sniffing valve. h is the equilibrium steam-admission valve for opening or closing the main steam port or inlet G . h' is the piston. p is the weight for assisting in closing the valve promptly. m is a screw-cap preventing the piston becoming displaced. t' is a ball-valve, arranged in the spindle of the steam-admission valve, and communicating with main steam-port by an aperture through which a loosely-fitting spindle, t' , passes, to the end of which is secured a float, t . The spindle of this description of steam-sniffing valve may

be provided with a collar, t'' , as shown, which, striking against the spindle of main steam-admission valve, will assist in forcing it from its seat.

Fig. 2 shows in part vertical longitudinal section this combined valve, marked with corresponding letters to that described with reference to Fig. 1. In this case a flat plate or disk, t , is used instead of a float, which, on receiving a blow from the rising water, operates the valve t' , opening into the main steam-passage.

Fig. 3 shows an arrangement similar to Fig. 2, except that the piston h' is shown provided with a valve-like end, h'' , which, on the piston h' and steam-valve h opening and rising, rests in a suitably-formed seating, and thus, while at the same time acting as a stop for the piston, prevents any leakage of the steam.

Fig. 4 shows an application of a diaphragm, q , to a similar description of these combined valves, the diaphragm taking the place of the piston.

The action of the apparatus—such as described in the before-mentioned specification, but fitted with this improved steam-sniffing valve—would be as follows, referring to Fig. 1: The body of the pump a and part of the rising main being supposed to be filled with fluid, the pump is started by turning on steam, or it may be necessary in some cases to raise and lower the valves h by hand, after which it will continue working automatically. The steam thus being admitted through the steam-supply G , it acts on the under sides of valves h and piston h' , and keeps the steam-supply passage open, and the pressure of the steam acting at the same time on the surface of the water forces it through the delivery-valve, the rising main, and the delivery-pipe.

The pressure of steam having fallen to or below the pressure of water in the rising main, sufficient water will be returned as a jet through an injection-pipe and hastens the formation of a vacuum. This vacuum causes the inflow of liquid through the suction-valves. The simultaneous closing of the steam-admission valves h and the rising liquid striking the float or disk t , will admit a small quantity of steam through the steam-sniffing valve t' , and the vacuum being thus destroyed the main

steam-valve will be opened, and this opening allows the steam again to act on the surface of the water, and the above-described round of operations will continue automatically.

5 I claim as my invention—

1. The combination, in a steam - vacuum pump, of the valves *h*, the steam-pipe *G*, vessel *A*, and connections, the float *t*, stem *t'*, passing through the tubular stem of the lower valve *h*, the valve *t'* at the upper end of the stem, and the piston *h'*, upon the stem of the upper valve *h*, substantially as set forth.

10 2. The combination, in a steam - vacuum pump, of the valves *h*, the steam-pipe *G*, ves-

sel *A*, and connections, the float *t*, stem *t'*, passing through the tubular stem of the lower valve *h*, the valve *t'* at the upper end of the stem, and the piston *h'*, upon the stem of the upper valve *h*, substantially as set forth.

C. BURNETT.
